TURBINE

Karl Baumann, Mere, Knutsford, England, assignor to Metropolitan-Vickers Electrical Company Limited, London, England, a company of Great Britain

Application January 13, 1944, Serial No. 518,174
In Great Britain January 19, 1942

5 Claims. (Cl. 230—116)

1

This invention relates to an internal combustion or gas turbine plant and is notably applicable to the connecting means between the arrangement of low pressure compressor blading stages and low pressure blading stages driving said compressor stages described with reference to Figs. 8 and 9 of the drawings accompanying the specification of U. S. application Serial No. 518,166, filed of even date herewith. The present invention, however, has a wider application and is applicable generally where a row or stage of blading such as of an axial flow compressor, and hereinafter referred to as of an outer system, surrounds blading of an inner system with which it has a driving connection, said outer blade row or stage being carried on a foundation ring of light alloy which is connected with one or more stages of the inner system through a driving member conveniently of steel which in part is in the form of a cylinder or a re-entrant cylinder or the like, attached at its radially outermost part to said foundation ring and at its radially innermost part to the blading of the inner system, for instance to the shrouding of the same, the connection being made thereto by providing the radially outermost part of the connecting member with an outward radial flange integral with a re-entrant cylindrical flange to provide an annular channel into which the edge of the foundation ring is axially inserted and fixed therein such as by a plurality of radial rivets.

The blade roots of the outer system, such as of dovetail form, may be extended in the axial direction beyond the blade so as to be also clamped within the annular channel between the aforesaid steel flanges.

Since the shape of the steel driving member for the foundation ring of the outer system of blading is chosen to provide some radial flexibility to permit of differential thermal expansion there will be left a small space between the inner surface of the foundation ring and the outer surface of the flexible steel member, and cooling air may be permitted to flow in the axial direction through this space by milling a plurality of channels in the extended end of the foundation ring connecting said annular space to a washer-shaped space which may be left within the channel of the steel connecting member, that is between the radial flange of the latter and the radial face of the extended end of the foundation ring, whilst holes may be drilled in the radial flange of the steel connecting member to permit the flow of the cooling air to or from this washer-shaped space.

2

Where two or more stages of the outer system are individually driven by corresponding sections of the inner system, for instance constituting a contra-rotating group, an axially extending lip from one driving member may project beneath the neighbouring driving member, and be so formed as to serve as a labyrinth gland therewith.

In the accompanying drawings,

Fig. 1 is a somewhat diagrammatical section of an embodiment of the present invention, and Fig. 2 is a like view of a second embodiment.

Fig. 3 is a fragmentary section of the foundation ring and adjacent parts of one of the stages of the outer system of blading; and

Fig. 4 is a detail section on the line 4—4 in Fig. 3.

For the sake of simplicity Figs. 1 and 2 of the accompanying drawings are identical with Figs. 8 and 9 respectively of the drawings accompanying the specification of U. S. application Serial No. 518,166 aforesaid, but, as hereinbefore pointed out, the present invention in respect of the specific features thereof has wider application than that to which the arrangements shown in the aforesaid Figs. 8 and 9 are claimed in the earlier application just mentioned, and, of course, the claims of the present application are to be interpreted as excluding anything claimed in said earlier application.

30 For convenience also the reference numerals used in Figs. 8 and 9 of said earlier specification are used again in the accompanying drawings.

In the accompanying drawings, 1, 2, 3 and 4 represent four consecutive rows of contra-rotational turbine blading, two stages of each being carried on respective inner and outer rotor cylinders and driving two stages I and II of an outer system of contra-rotational blading fragmentally shown, the foundation rings Ia and IIa being essentially (as part of the present invention) of "light alloy" and having longitudinal dovetail or equivalently shaped grooves receiving the correspondingly shaped roots of the blades I and II.

For a full description of the inner and outer 45 rotor cylinder members of the contra-rotational turbine reference should be had to the specification of the aforesaid U. S. application. The outer rotor cylinder comprises the shrouding rings 2d and 4d united by riveting, with a sleeve member 3, which, in the arrangement shown in Fig. 1 of the accompanying drawings, is provided with a cylindrical extension 8e which is riveted at 8f to the cylindrical sleeve member 10 to provide 50 flexible driving connection between the blade rows 2 and 4 of the inner system and the outer blad-

ing row II whilst the shrouding ring 1d of the stage I of the inner rotor cylinder comprising the contra-rotational stages I and 3 has riveted to it the internal flange of a corresponding cylindrical member 8c which is riveted at 9b to the flexible steel cylindrical member 9. The inner and outer rotor cylinders are carried by rotor discs 5 and 6 respectively.

The cylindrical members 9 and 10 are, in general, of substantially the same shape, the axially extending member 9 forming with the member 8c a "swan-neck" device formed at its left-hand end with a radial flanged portion 9f integral with which is a re-entrant cylindrical flange 9m, thereby providing as shown the annular channel holding, by the radial rivets 9n, the inserted extension edge of the foundation ring 1a and also the extension of the blade root 1b which is fixed in axial grooves in the "light alloy" ring 1a as shown in Figs. 3 and 4.

An annular shield member 20 is clamped through its cylindrical portion by the rivets 9b on the members 8c and 9 and an annular deflector member 21 is fixed by the rivets 8f to the members 8c and 10. There are also holes p as shown in the radial parts 9f of the channel members. These foundation rings 1a and 11a necessarily have cylindrical clearance from the outer parts of the cylindrical members 9 and 10. Thus, as shown by the short arrows 22 and 23, cooling air, due to pressure difference, flows back from the deflector 21 to the axial grooves 24 in the foundation ring 2a to and through the holes p and then through the grooves 25 in the foundation ring 1a, along the similar space between the parts 1a and 9 as indicated by the arrow 23a, to the shield 20 to be returnable to the annular stream of air or gas worked upon by the blading I and II. The grooves 25 in the ring 1a are shown in Figs. 3 and 4, and it will be understood that the grooves 24 in the ring 11a are similar thereto but relatively reversed.

At 10a is shown a lipped flange on the member 10 co-operating with the left-hand end of the member 9 to form packing.

The arrangement shown in Fig. 2 of the accompanying drawings differs only in detail from the arrangement shown in Fig. 1. At 26 is shown in dotted lines the final blading stage of a turbine driving the compressor which supplies the combustion chamber exhausting into said turbine and thence passing products into the turbine blading stages I to 4. At 27 and 28 are fragmentarily shown labyrinth packing members separating the moving parts from the last stage 26 of the compressor turbine, as will be well understood by those skilled in the art. There are also shown in Fig. 2 ventilation holes V1 and V2 and the cylindrical extension V3 of the member 8c for preventing the "light alloy" foundation rings of the outer blading system being subjected to too high temperatures. These ventilation holes permit fluid circulation from the turbine inlet as indicated by the arrow 29 through the hole V1, then beneath the extension V3, and then through the hole V2, and escaping past the periphery of the shrouding ring 4d. The steel holding member for the "light alloy" blading roots 11a is formed with a cylindrical flange 10b overlapping a cylindrical extension 9q on the member 9, labyrinth packing being provided between these members, as shown.

I claim:

1. In apparatus of the character described comprising an outer blading system and an inner bladed system surrounded by said outer system, a foundation ring of light alloy for at least one row of blading of said outer system, a driving member of reentrant form connected with at least one row of blading of said inner system, said driving member having an outer flange and an axially extending reentrant flange to provide an annular channel into which said foundation ring extends, and means attaching said ring in said channel.

2. In apparatus of the character described comprising an outer blading system and an inner bladed system surrounded by said outer system, a foundation ring of light alloy for at least one row of blading of said outer system, a driving member of reentrant form connected with at least one row of blading of said inner system, said driving member having an outer flange and an axially extending reentrant flange to provide an annular channel into which said foundation ring extends, said row of blading of the outer system also having blade roots extended axially beyond the blades and received in said annular channel, and means attaching said ring in said channel.

3. In apparatus of the character described comprising an outer blading system and an inner bladed system surrounded by said outer system, a foundation ring of light alloy for at least one row of blading of said outer system, a driving member of reentrant form connected with at least one row of blading of said inner system, said driving member having an outer flange and an axially extending reentrant flange to provide an annular channel into which said foundation ring extends, and means attaching said ring in said channel, the inner surface of said foundation ring having a clearance from said driving member and said ring and member having a passage for the circulation of cooling fluid communicating with said clearance.

4. In apparatus of the character described comprising an outer blading system and an inner bladed system surrounded by said outer system, a foundation ring of light alloy for at least one row of blading of said outer system, a driving member of reentrant form connected with at least one row of blading of said inner system, said driving member having an outer flange and an axially extending reentrant flange to provide an annular channel into which said foundation ring extends, means attaching said ring in said channel, and fluid deflecting means carried by said member to deflect cooling fluid into said structure.

5. In apparatus of the character described comprising an outer blading system and an inner bladed system surrounded by said outer system, a foundation ring of light alloy for at least one row of blading of said outer system, a driving member of reentrant form connected with at least one row of blading of said inner system, said driving member having an outer flange and an axially extending reentrant flange to provide an annular channel into which said foundation ring extends, means attaching said ring in said channel, and heat shielding means carried by said driving member and interposed between said foundation ring and the blading of the inner system.

KARL BAUMANN.
